UNITED STATES PATENT OFFICE.

JOHN LOOS, OF FREEPORT, ILLINOIS.

DESIGN FOR A FRAME FOR BALL-CASTERS.

SPECIFICATION forming part of Design No. 31,597, dated October 3, 1899.

Application filed August 31, 1899. Serial No. 729,131. Term of patent 14 years.

To all whom it may concern:

Be it known that I, JOHN LOOS, a citizen of the United States, residing at Freeport, in the county of Stephenson and State of Illinois, 5 have invented and produced a new and original Design for a Frame for Ball-Casters, of which the following is a specification, reference being had to the accompanying drawings, forming part thereof.

10 Figure 1 is a side view of the ball-caster frame, the ball itself being omitted. Fig. 2 is an axial section perpendicular to the line of sight in Fig. 1.

15 As shown in the figures, my novel design is embodied in a caster-frame consisting, essentially, of a body A below, a stem B above, and an annular horizontal disk or flange C at the junction of the body and stem. The body has approximately the form of an egg with a 20 small portion of its lower end cut away by a plane perpendicular to the egg's longer axis and having its surface curved outward near the smaller end to meet the flange C. As seen in Fig. 2, the lower part of the body is 25 hollow or a downwardly-open shell, the walls in passing upward from the lower limit of the

body first diverging, then turning abruptly inward to form a sort of annular shoulder D, and then gradually converging to meet a small plane surface E at the top of the cavity. The 30 proportions of the cavity are such that the same sphere might touch at the same time the plane surface, the shoulder D, and the lower margin of the cavity without touching elsewhere. A line F divides the whole surface 35 (external and internal) into halves, except that it does not appear on the flange or disk nor on the plane surface at the top of the cavity.

Having described my invention, what I 40 claim as new, and desire to secure by Letters Patent, is—

The design for a frame for ball-casters, herein shown and described.

In testimony whereof I have signed this 45 specification in the presence of two subscribing witnesses.

JOHN LOOS.
